UNITED STATES PATENT OFFICE

165,987

FAUCET

Kurt Krafft, Louisville, Ky., assignor to American Radiator & Standard Sanitary Corporation, Pittsburgh, Pa., a corporation of Delaware

Application April 14, 1951, Serial No. 14,846

Term of patent 14 years

(Cl. D91—3)

To all whom it may concern:

Be it known that I, Kurt Krafft, a citizen of the United States, residing at Louisville, State of Kentucky, have invented a new, original, and ornamental Design for a Faucet, of which the following is a specification, reference being had to the accompanying drawings, forming a part of.

Figure 1 is a top plan view of the faucet, embodying my new design;

Fig. 2 is a view in front elevation thereof;

Fig. 3 is a view in end elevation, looking from the left to right facing Fig. 2;

Fig. 4 is a view in perspective.

The dominant features of my design reside in the portions shown in solid lines.

I claim:

The ornamental design for a faucet, substantially as shown and described.

KURT KRAFFT.
